UNITED STATES PATENT OFFICE.

LINN K. PARK AND MARGIA MANNING, OF HOUSTON, TEXAS.

PUMP-OPERATING MEANS.

Application filed October 11, 1923. Serial No. 687,902.

To all whom it may concern:

Be it known that we, LINN K. PARK and MARGIA MANNING, citizens of the United States, residing at Houston, Texas, have invented a certain new and useful Improvement in Pump-Operating Means, of which the following is a specification.

Our invention relates to hoisting apparatus particularly adapted for use on oil 10 pumping installations for handling the tubing and rods when they are withdrawn from the well in the process of cleaning or renewing the pumping apparatus.

In the usual standard pumping rig, a 15 band wheel is operated from an engine to actuate the walking beam and from the band wheel a bull wheel on the opposite side of the derrick platform is rotated by means of a bull rope or bell connection with the band 20 wheel. This bull wheel installation is heavy and expensive. It occupies valuable space on the derrick platform. It is slow in operation and occupies a dangerous position for the operator.

25 It is the object of our invention to provide a small and compact hoisting apparatus, which is light, easily portable, and which may be installed adjacent the band wheel or other source of power, thereby using little space on the platform. It will be safe to operate and will handle the pulling quickly and expeditiously.

Another object is to provide a hoisting apparatus which may be easily reversed 35 without strain or jar upon the operating mechanism, thereby avoiding danger of breakage when the tubing, rods or bailer catches in the well.

These and other objects and advantages 40 will be set forth with greater particularity in the specification which follows:

Referring to the drawing herewith, wherein like numerals of reference designate like parts in all the views: Fig. 1 is a 45 front elevation of an installation embodying the invention, certain parts being broken away for greater clearness; Fig. 2 is an end elevation thereof; and Fig. 3 is an elevation viewed from the opposite end.

50 In the drawings, the device is shown as supported by two upright end members 1 and 2 connected with the derrick and a base formed by the derrick floor 3. The cable drum 4 is mounted rotatably upon a 55 shaft 5 supported at its ends in bearings 6, secured rigidly upon the supports 1 and 2.

The supports being inclined somewhat, the bearings consist of a triangular base block 7, having a forward bearing recess 8 therein. A removable upper bearing plate 9 is 60 clamped upon said base plate 7 by bolts or screws 10 thus securing the shaft firmly in place.

The drum 4 is materially shorter than 65 said shaft and is mounted midway thereof so that its ends are spaced from the supports 1 and 2. Said drum comprises a spool shaped reel having bearings 11 at each end. On the outer faces of both of the radial 70 end flanges 12 are formed the brake drums 13 of ordinary construction adapted to receive the brake bands 14 operated by the brake rod 15 having a hand lever 16 thereon.

Immediately adjacent the outer end of 75 each bearing hub 11 are sleeves 17, 17, having bearings 18 on the shaft 5. Fixed non-rotatably on the inner end of sleeve 17 is a collar 19 having thereon a spider 20 the outer periphery 21 of which forms a stop member for discs 22 of a friction clutch. 80

Slidable on said sleeve 17 is a clutch actuating collar 23 having a toggle connection 24 with the friction disc engaging band 25. The collar 23 is slidable on said sleeve 17 by means of a lever 26 pivoted at its upper 85 end at 27 to a cross piece 28 connected with a supporting frame. This lever is connected in the usual manner to the sliding clutch collar and at its lower end adjacent the platform 15, it has a pivotal connection with a rod 28.

As will be noted from Fig. 1, the rod 28 is adapted to operate the clutch levers at both ends of the reel. The rod is actuated by 90 means of a lever 29 connected at 30 to the rod 28 and at its lower end beneath the derrick platform it is connected to a rod 31, connecting the lever 29 with a lever 32 projecting downwardly from the pedal 33. This pedal is fixed to a pin 34 having a 95 bearing upon the platform of the derrick. Said pedal is adapted to be operated in either direction, so as to connect one friction clutch with the reel at the same time the clutch at the opposite end of the reel 100 is disconnected. When the said pedal is in neutral position, as shown in Fig. 1, both clutches are released from engagement with the reel.

The sleeves 17 are operated by means of 110 sprocket wheels 35, 36, at the outer ends of said sleeves. Said sprocket wheels are keyed

to the sleeves and the sprocket wheel 35 is operatively connected with a sprocket wheel 37 mounted upon a countershaft 38 by means of a sprocket chain 39.

6 The countershaft 38 is mounted upon the upright supports 1 and 2 by means of bearings 40 similar in construction to the bearings 7 for the shaft 5. The sprocket wheel 35, at one end of shaft 5, is connected with 10 the sprocket wheel 37, as previously noted, and the sprocket wheel 36 at the opposite end is adapted to be operated by means of a chain 43 connected with some source of power, such as a sprocket wheel upon the 15 band wheel shaft or directly with some engine or motor. The chain 43 is, as shown in Fig. 3, adapted to run the sprocket wheel 36 and also engage the sprocket wheel 42 so as to operate the shaft 38 in a direction 20 opposite to the direction of rotation of the sprocket wheel 36. It will be noted that the operation of a chain 43 will cause the continuous rotation both of the sprocket wheel 36 and the countershaft 38 to which the 25 sprocket wheel 42 is connected. The connection between the sprocket wheel 37 and the sprocket wheel 35 will cause the continuous rotation of these two members, but in a direction opposite to the rotation of the 30 sprocket wheel 36. It will then only be necessary to connect one or the other of the sleeves 17 to the reel 4 by means of a friction clutch already described.

35 In the operation of our improved device, the rotation of the sprocket wheels will be accomplished in the manner described, and when it is desired to reel up the cable upon the drum in hoisting operations, the friction clutch connecting the sprocket wheel 36 and 40 the sleeve upon which it is mounted to the reel will be put in engagement, thus serving to drive the reeling mechanism in the same direction in which the engine is rotating. If it is desired to stop the reeling mechanism, the pedal 33 is employed to throw the 45 friction clutch into neutral position and the brake is then employed to bring the reel to a stop. If it is then desired to lower the rods or tubing into the well, the weight of 50 the parts to be lowered will be sufficient to unreel the cable from the reel 4 if the brake band is loosened through the operation of the lever 16. If, however, it is necessary to use the motive power to turn the reel in the 55 lowering direction, the throwing of the friction clutch into reversing position will connect the countershaft 38 with the sprocket wheel 35, and the friction clutch at that end 60 may be engaged with the reel so as to positively rotate it in the unreeling direction.

The advantages of this type of construction will be obvious to one skilled in the art. The device is simple and compact and occupies little space upon the derrick platform. It may be rotated in either direction without reversing the direction of rotation of the engine and the reel may be operated by the clutch mechanism without any jerk or jar upon the operating parts by the gradual connection of the clutch to the reel. This 65 reel may be gradually engaged while the engine is running at high speed and may be likewise disengaged without any effect upon the source of power. This is particularly 70 advantageous in operating the setting or removal of the tubing or rods when the parts become stuck or hung up in the hole. The clutch will slip before the rods or tubing, or the cable attached thereto, has an opportunity to break. The parts being of light construction, the weight of the rods or tubing will, under most circumstances, be entirely sufficient to unreel the cable from the hoisting mechanism, and in such case the clutches 75 will be placed in neutral position and the speed of the reel will be limited by the operation of the brake bands upon the brake drums. A hoisting mechanism of this kind is not only light and compact, but cheap in 80 construction and may be operated at a much 85 cheaper cost than the type of mechanism now ordinarily employed. It is also safer to operate and may be easily housed at the side of the derrick. Its further objects and 90 advantages will be obvious to those skilled 95 in the art.

What we claim as new and desire to protect by Letters Patent is:

A hoisting apparatus for well pumping equipment, comprising upright supports, a 100 shaft, a cable reel rotatably mounted thereon, a brake drum on each end of said reel, brake bands on said drums, and means to operate said reel on said shaft comprising, a sleeve on said shaft at each end thereof, a 105 sprocket wheel fixed on each sleeve, a friction clutch between said sleeves and said reel, a counter shaft on said supports, sprocket wheels at each end thereof, a 110 sprocket chain connecting the sprocket wheels on said shafts at one end thereof and a drive chain from a source of power adapted to drive said sprocket wheels at the other end in opposite directions.

In testimony whereof, we have hereunto affixed our signatures this the 6th day of October, A. D. 1923.

MARGIA MANNING.
